UNITED STATES PATENT OFFICE

150,885

DESIGN FOR A DISPENSING DEVICE FOR
COLLAPSIBLE TUBE

William E. Richardson, Detroit, Mich.

Application May 13, 1946, Serial No. 129,639

Term of patent 3½ years

(Cl. D4—3)

To all whom it may concern:

Be it known that I, William E. Richardson, a citizen of the United States of America, residing in Detroit, in the county of Wayne, State of Michigan, have invented a new, original, and ornamental Design for Dispensing Device for Collapsible Tube, of which the following is a specification, reference being had to the accompanying drawing, forming a part thereof, wherein:

Figure 1 is an elevational view of a dispensing device for collapsible tube, illustrating my novel design;

Fig. 2 is a side view of the dispensing device illustrated in Fig. 1, and

Fig. 3 is a bottom view of the dispensing device illustrated in Fig. 1.

I claim:

The ornamental design for a dispensing device for collapsible tube, substantially as shown.

WILLIAM E. RICHARDSON.
